ARCH LIFT

Maria G. Waksmundzka, Washington, D. C.

Application February 25, 1933. Serial No. 658,602

REISSUED

2 Claims. (Cl. 36—71)

My invention is an arch lift.

As is well known, the condition of falling arch of the foot is caused by the lowering of the internal cuneiform and first metatarsal bones, which is caused by the giving away of the muscles and ligaments adjacent to the articulated surfaces. These bones have an outer generally concave outline in a longitudinal direction.

I have discovered that if a flexible and resilient lifting pad is arranged upon the arch of the foot, adjacent to these bones, and of suitable shape and size so that it will exert a proper upward and inward pressure upon these bones, near their articulated surfaces, that these bones will be gradually lifted and restored to their normal position. When this is done, ordinarily the remaining bones of the foot follow, and return to the normal position, and the foot is restored to its normal strength and flexibility.

20 The lifting pad, due to its flexibility and resiliency in use, serves to exercise and massage the muscles and ligaments adjacent to these bones, thereby strengthening the same and aiding in correcting the condition.

25 In the accompanying drawing, forming a part of this specification, and in which like numerals are employed to designate like parts throughout the same,

Figure 1 is a plan view of an arch lift embodying my invention,

Figure 2 is an end elevation of the same,

Figure 3 is a transverse section taken on line 3—3 of Figure 1,

Figure 4 is a horizontal section taken on line 35 4—4 of Figure 2, and,

Figure 5 is a plan view of the bones of the foot, illustrating the application of the device to the same.

In the drawing, wherein for the purpose of illustration is shown a preferred embodiment of my invention, the numeral 10 designates an attaching sole, which is advantageously formed of thin flexible material, such as leather. This attaching sole embodies a heel portion 11, a sole portion 12, and a restricted intermediate portion 13.

The numeral 14 designates a lifting pad, which is flexible and resilient. This pad is preferably formed of rubber and is compressible and relatively silent, but is not as compressible as sponge rubber. The degree of compressibility of the rubber may vary, and I have found that satisfactory results are obtainable by using a rubber having substantially the same degree of compressibility as is found in the ordinary office rubber band.

An important feature of the invention is the precise shape and arrangement of the lifting pad 14. This lifting pad is longitudinally curved, as shown as Figure 4, and has an inner convex

dition to this, the pad tapers throughout its entire length, terminating in relatively thin edges 17. The free edge of the pad is also curved in a more or less vertical plane.

Figure 3 illustrates the precise shape of the 65 pad 14, in cross section. This pad tapers upwardly to a thin edge 18, and tapers downwardly to a thin edge 19, with its innermost contact portion 20, near its center. The general shape of the inner face 15 of the pad is spherical, the same being 70 convex both vertically and horizontally.

The pad 14 is mounted upon the attaching sole 10, with the adjacent edge of the sole preferably engaging about the outer side of the pad, at its marginal edge, these parts being secured 75 together by cement or the like.

The effectiveness of the device depends largely upon the fact that it is made in precisely the correct shape and size, for each foot and shoe, and it is therefore, necessary that the device 80 must be made in sizes corresponding to the sizes of the shoes. The device is arranged within the shoe so that the lifting pad 14 will be adjacent to the inner longitudinal arch of the foot. The attaching sole is made in the proper size and 85 shape for the particular shoe, and is so correlated with the lifting pad 14, that when the attaching sole is properly located in the shoe to coincide with the shoe sole, the lifting pad will be in the correct position. After being 90 properly located in the shoe, the attaching sole is cemented to the shoe sole. This holds the lifting pad against being displaced bodily, but due to the flexibility of the attaching sole and pad, the pad may flex or yield, during the walking action, so that it will properly massage and exercise the adjacent muscles and ligaments.

Figure 5 indicates the position that the lifting pad assumes with respect to the bones of the foot. It will be noted that the internal cuneiform and first metatarsal bones, at their outer sides, assume a generally convex relation in a longitudinal direction, covered of course by the flesh.

The convex shape of the face 15 permits the lifting pad to conform generally to this relation of these bones. Further, the convex

face of the pad is so shaped that it exerts the maximum pressure upon the inner portions of the internal cuneiform and first metatarsal bones, and also adjacent to their inner articulated surfaces.

It will be noted that the portion 20 of the pad 14 is arranged adjacent to and opposite the articulated ends 20' of the internal cuneiform and first metatarsal bones. The edge or line 19 constitutes the effective edge of 115 attachment between the lifting pad 14 and sole 10.

The pad 14 is transversely inclined and projects laterally beyond this effective edge of attachment 19. The entire area of the lifting pad 14 is therefore arranged outwardly of the 120

effective edge of attachment 19. As a result of this arrangement, the maximum point of protuberance 20 is also disposed outwardly of this effective edge of attachment 19. This arrangement is accomplished by locating the lifting pad at the effective line of attachment 19, whereby the entire area of the sole 10 which extends under the foot, which is that area of the attaching sole 10 between the edge 19 and the 5 opposite edge of the attaching sole, is entirely uncovered by the lifting pad. This preserves the thin character of the attaching sole 10 beneath the foot, which is important. By virtue of the precise arrangement of the lifting pad and attaching sole, the lifting pad exerts vertical and horizontal forces upon the longitudinal side arch of the foot and a resultant force at an angle of substantially 45° from the horizontal passing through the maximum point of protuberance 20, 10 and acting upon that end of the first metatarsal bone adjacent to the cuneiform bone. This force at an angle of substantially 45° from the vertical not only serves to elevate this end of the first metatarsal bone, but also serves to turn 15 the end of the bone inwardly, restoring it to its normal position. Particular attention is called to the fact, as shown in Figure 5, that the inner face of the lifting pad 14 is sufficiently long to extend over the first metatarsal, internal cuneiform and scaphoid bones, exerting pressure upon 20 all of them. This lifting force is in two general directions, namely, upwardly and horizontally, at generally a right angle to each other, as shown at Figure 3, with the resultant force 25 in an inclined direction at an angle of approximately 45 degrees from the horizontal. These forces are indicated by the arrows in Figure 3. The pad 14 therefore exerts an upward and lateral pressure upon these bones, which pressure is continuous but yieldable, with the result 30 that the bones are free to move properly, but are lifted or supported and worked back to the normal elevated positions. Due to the flexibility and resiliency of the pad 14, it not only serves 35 to elevate these bones, but also serves to massage and exercise the adjacent muscles and ligaments, which in turn, strengthens the foot and aids in its return to a normal condition. The lifting pad 14 does not extend under the sole 40 of the foot, to any considerable distance, and therefore does not function to exert any true vertical lifting action. This lifting pad serves to apply a lifting force to the side face of the arch, which maximum force is exerted generally upwardly at the inclination of about 45 degrees 45 from the horizontal.

It is to be understood that the form of my invention herewith shown and described, is to be taken as the preferred example of the same, 50 and that various changes in the shape, size and arrangement of parts may be resorted to without departing from the spirit of my invention or the scope of the subjoined claims.

Having fully described my invention, what I 55 claim is:—

1. A device for lifting the inner longitudinal arch of the foot, said device being made in the proper size corresponding to the size of the shoe being worn, said device comprising a relatively 60 thin attaching sole including a heel portion and an intermediate portion having a curved edge adjacent to the inner longitudinal arch, said attaching sole being adapted to be secured to the shoe in the correct position therein, and a flexible and resilient lifting pad secured to the at-

taching sole adjacent to the curved longitudinal edge thereof, the effective edge of attachment between the sole and pad being such that the major portion of the sole beneath the foot is uncovered by the pad, the lifting pad being transversely inclined and having the major portion of its area projecting laterally beyond the said effective edge of attachment, the lifting pad having a face which is longitudinally convex and transversely convex and having a maximum point of protuberance arranged near the center of such face, the lifting pad being so positioned upon the attaching sole that the maximum point of protuberance is arranged beneath and in substantial transverse vertical alignment with the articulated ends of the internal cuneiform and first metatarsal bones, the location of the lifting pad at the effective edge of attachment and its transverse inclination above and laterally beyond such effective edge of attachment bringing the maximum point of protuberance laterally outwardly of such effective edge of attachment thereby causing the lifting pad to exert substantially vertical and horizontal pressures upon the inner longitudinal arch and resultant pressure at an angle of approximately 45° from the horizontal through the maximum point of protuberance which will elevate the end of the first metatarsal bone adjacent to the internal cuneiform bone and turn the same inwardly to 105 the normal position.

2. A device for lifting the inner longitudinal arch of the foot, said device being made in the proper size corresponding to the size of the shoe being worn, said device comprising a relatively thin attaching sole including a heel portion and an intermediate portion having a curved edge adjacent to the inner longitudinal arch, said attaching sole being adapted to be secured to the shoe in the correct position therein, and a flexible and resilient lifting pad secured to the attaching sole adjacent to the curved longitudinal edge thereof, the effective edge of attachment between the sole and pad being such that the major portion of the sole beneath the foot is 110 uncovered by the pad, the lifting pad being transversely inclined and having substantially its entire area projecting laterally beyond the said effective edge of attachment, the lifting pad having an inner face which is longitudinally convex and transversely convex and having a maximum point of protuberance arranged near the center of such inner face, the inner face being of such a length that it extends over and exerts pressure upon the first metatarsal, internal cuneiform and scaphoid bones, the lifting pad being so positioned upon the attaching sole that the maximum point of protuberance is arranged beneath and in substantial transverse vertical alignment with the articulated ends of the internal cuneiform and first metatarsal bones, the location of the lifting pad at the effective edge of attachment and its transverse inclination above and laterally beyond such effective edge of attachment bringing the maximum point of protuberance laterally outwardly of such effective edge of attachment thereby causing the lifting pad to exert substantial vertical and horizontal pressures and a resultant pressure at an angle of approximately 45° from the vertical through the maximum point of protuberance which will elevate the end of the first metatarsal bone adjacent to the internal cuneiform bone and turn the same inwardly to the normal position.
